UNITED STATES PATENT OFFICE.

WALTER F. KNOX, OF BIDDEFORD, MAINE.

DRAWING AND MEASURING DEVICE.

Application filed January 8, 1920, Serial No. 350,155. Renewed November 20, 1922.

To all whom it may concern:

Be it known that I, WALTER F. KNOX, a citizen of the United States, residing at Biddeford, in the county of York and State of Maine, have invented new and useful Improvements in Drawing and Measuring Devices, of which the following is a specification.

This invention relates to improvements in drawing and measuring devices, and has for its object the provision of a simple and inexpensive device for making drawings to scale when ordinary drafting appliances are not available, as when preparing sketches in the field.

With the above stated object in view, the invention comprises the new and useful details of construction and arrangement, which will be fully described herein, illustrated in the annexed drawing, and claimed more specifically hereinafter.

In the drawings, wherein the preferred embodiment of the invention is shown, the figure is a top plan view of the improved drawing and measuring device.

The device comprises a forty-five degree triangle 1 and a straight edge 3, the latter being placed on the drawing paper and fastened down thereon by thumb tacks or other suitable means passed through perforations 7 near the ends of the straight edge. The straight edge 3 will be positioned diagonally on the drawing paper at such an angle that when the triangle 1 is placed in edgewise contact therewith as shown in full lines in the drawing, the hypotenuse edge 2 of the triangle may be used for guiding the pencil or drawing instrument to draw horizontal lines. If the sheet of drawing

paper is rectangular and it is desired to have the horizontal lines of the drawing parallel to the top and bottom edges of the sheet, the straight edge 3 must be placed at an angle of forty-five degrees to said edges.

However, this is not necessary and the outline of the sheet may be disregarded, the straight edge 3 being placed at any convenient angle and used to guide the triangle 1 in the manner stated to draw lines running across the sheet in the direction of the sides thereof, these to be the horizontal lines of the drawing. Vertical lines are drawn by turning over the triangle 1 placing it as shown dotted in the drawing, the hypoth-

enuse edge 2 now running in the direction of the top and bottom edges of the sheet, so that when the pencil or drawing instrument is guided along said edge it will make lines which are perpendicular to the horizontal lines which were drawn when the triangle was in the first described position.

In either one of the two hereinbefore described positions of the triangle, one of its edges 4 adjacent to the hypotenuse edge 2 is placed in contact with the edge of the member 3, as clearly shown in the drawing, and by sliding the triangle along the latter edge, parallel lines may be drawn, the hypotenuse edge 2 of the triangle 1 having a graduated scale so that the required length of these lines may be readily obtained.

In order that the distance between the parallel lines may be accurately measured, the edge of the member 3 which guides the triangle 1 has a graduated scale 5. To enable readings to be taken directly from this scale, its graduations denote actual distances between parallel lines drawn along the hypotenuse edge 2, but as the member 3 extends obliquely or diagonally with respect to these parallel lines the distances between the graduations are greater than the actual distances denoted thereby, the difference being proportionate to the angle of the member 3 relative to the parallel lines drawn along the edge 2.

From the foregoing description it will be apparent that the present invention provides a simple and inexpensive device for making drawings to scale, especially adapted for use in the field where ordinary appliances are not available.

I claim:

A drawing device comprising a straight edge and a forty-five degree triangle, the straight edge being adapted to be positioned diagonally on the drawing surface, and the triangle adapted to be positioned with one of its edges which is adjacent to its hypotenuse edge in sliding contact with the straight edge, to position said hypotenuse edge horizontally or vertically on the drawing surface, the straight edge having graduations denoting actual distances between parallel lines drawn along the hypotenuse edge.

In testimony whereof I affix my signature.
WALTER F. KNOX.
